(57) CLAIM

The ornamental design for a solar golf cup cover, as shown and described.

DESCRIPTION

FIG. 1 is a top perspective view of a solar golf cup cover showing my new design;

FIG. 2 is a top view in plan thereof;

FIG. 3 is a bottom view in plan thereof;

FIG. 4 is a front view in elevation thereof;

FIG. 5 is a right side elevation view thereof;

FIG. 6 is a left side view in elevation thereof; and,

FIG. 7 is; a left side elevation view thereof.

The broken lines showing a solar collector, light emitting diodes, screws, lettering and buttons are included for the purpose of illustrating unclaimed subject matter and forms no part of the claimed design.

1 Claim, 5 Drawing Sheets
